US00D822058S

(12) **United States Design Patent** (10) **Patent No.:** **US D822,058 S**
(45) **Date of Patent:** **** Jul. 3, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **Lee Broughton**, Santa Cruz, CA (US);
Gary Butcher, San Jose, CA (US);
Aled Williams, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/616,007**

(22) Filed: **Sep. 1, 2017**

Related U.S. Application Data

(63) Continuation of application No. 29/567,690, filed on Jun. 10, 2016, now Pat. No. Des. 796,543.
